UNITED STATES PATENT OFFICE.

GEORGE B. GIFFORD, JR., OF BAYONNE, NEW JERSEY.

HEAT-ABSORBING SYSTEM FOR INTERNAL-COMBUSTION ENGINES.

1,261,734.

Specification of Letters Patent.

Patented Apr. 2, 1913.

Application filed May 25, 1917. Serial No. 170,882.

To all whom it may concern:

Be it known that I, GEORGE B. GIFFORD, Jr., a citizen of the United States, and a resident of Bayonne, in the county of Hudson and State of New Jersey, have invented a new and Improved Heat-Absorbing System for Internal-Combustion Engines, of which the following is a full, clear, and exact description.

10 This invention relates to what may be termed heat absorbing systems for internal combustion engines, and has for an object the provision of an improved construction whereby the heat absorbed from the engine 15 is communicated to air supplied to the carbureter.

Another object of the invention is to provide a heat absorbing or cooling system whereby radiators for internal combustion 20 engines for automobiles and for other purposes are eliminated.

A further object of the invention is to provide a more uniform and even condition in respect to the heat of the cylinders and 25 the incoming fuel.

In the accompanying drawing:—

Figure 1 is a side view of an engine with an embodiment of the invention applied thereto, certain parts being broken away for 30 better illustrating the construction.

Fig. 2 is a transverse sectional view through Fig. 1 on line 2—2.

Fig. 3 is a top plan view of one end of the heat absorbing member shown in Fig. 1, the same being on an enlarged scale.

40 Referring to the accompanying drawing by numerals, 1 indicates an engine of any desired kind which may be used at any place, as for instance, on an automobile, and when so used the engine is arranged so that 45 the pipe 4 will be at the front so that the air may travel in the direction of the arrow 3 and pass through the opening in pipe 4 into the heat absorbing member 5. Member 5 comprises a shell 6 of metal or any suitable material connected with the headers 7 and 8, said headers being hollow and connected by tubes 9 whereby air entering the opening in pipe 4 will fill header 8 and pass

through the tubes 9 to header 7 and from thence out the discharge opening 10 into pipe 11. The air passing through pipe 11 will be discharged into the carbureter 12 through the primary inlet 13 and also through the auxiliary air inlet 14.

The engine 1 is provided with water jackets 15 and 16 for the respective cylinders, said water jackets being connected with the pipes 17 and 18, said pipes extending through the header 8 but connected therewith so as to make a water-tight fit, whereby the water from the water jackets may freely pass into the space above header 8 and circulate around between the tubes 9. Preferably, when the water jackets 15 and 16 are supplied with water through the inlet pipe 19 sufficient water is used to fill the water jackets and also to substantially fill the space between headers 7 and 8.

By this construction and arrangement, as the water is heated by the respective cylinders said water will rise and the cooler water in the space or chamber 20 between the headers 7 and 8 will move downwardly. This upward and downward movement of the water continues as long as the engine is in use because of the fact that the air passing through tubes 9 into the headers continually produces a cooling effect by absorbing the heat units from the water. This will not only cool the water so that the water may act properly on the cylinders but the heat units thus removed from the water are utilized for heating the air and the heated air is utilized by the carbureter 12, so that a fuel fed into the cylinders will be at a temperature more nearly equal the temperature of the cylinder, thus giving a better and more uniform combustion and a more uniform action of the engine. The tubes 9 may be threaded into place or screwed into place in any suitable manner, as well as the remaining parts may be connected together in any suitable manner as long as the structure will provide for a circulation of water as described and also a circulation of air. The pipes 17 and 18 are shown as connected to the top of the casing but these pipes could be connected to the side or at any suitable point without departing from the spirit of the invention. The tubes 9 are connected to the top and

bottom plates of the headers so that the air and water will be entirely separate. These tubes may be held in place in any suitable manner without departing from the spirit of the invention.

What I claim is:

1. In a heat absorbing device for internal combustion engines, the combination with an engine having a water jacket, of a casing 10 connected with said water jacket so that the water in the water jacket and the water in the casing may freely circulate, said casing being provided with a plurality of air pipes and a header at each end of said air pipes, 15 means forming an air inlet for one of said headers, and a pipe connected to the other header through which the heated air is discharged, said last mentioned pipe extending to the carbureter of said engine supplying

heated air to main and auxiliary air inlets 20 thereof.

2. In a device of the character described, the combination with an internal combustion engine provided with a water jacket and a carbureter, of means arranged above 25 the engine for absorbing heat units, said means including a space for the circulation of water, an air compartment above and below said water space and pipes connecting said compartments, means for connecting 30 the space for circulating the water with the water jacket, and means for connecting the upper air compartment with said carbureter whereby the temperature of the water is reduced and the temperature of the air supplied to the carbureter raised.

GEO. B. GIFFORD., JR.
